UNITED STATES PATENT OFFICE.

EMIL RATTEY, OF NEW YORK, N. Y.

DASH-BOARD.

SPECIFICATION forming part of Letters Patent No. 256,370, dated April 11, 1882.

Application filed January 20, 1882. (Model.)

To all whom it may concern:

Be it known that I, EMIL RATTEY, of the city, county, and State of New York, have invented a new and useful Improvement in Dash-
5 Boards, of which the following is a full, clear, and exact description.

My invention relates to dash-boards for sleighs; and it consists in a board formed of wire-netting attached to a frame of tubing, as
10 hereinafter described and claimed.

Reference is to be had to the accompanying drawings, forming part of this specification, in which similar letters of reference indicate corresponding parts in both the figures.

15 Figure 1 is a front elevation of a dash-board of my improved construction, the frame being partially broken away, and Fig. 2 is a cross-section on line $\alpha\alpha$ of Fig. 1.

The main frame A of the dash-board, which
20 is attached to the sleigh-body, is composed of end rods, a , and longitudinal rods b . Within this frame is an inner frame, B, composed of tubes c , to which the wire-netting d is fastened. The tubes c are slotted lengthwise to receive
25 the edges of the netting, and the edges of the longer sides of the netting are provided with a rib or bead, e , which in the example shown consists of a narrow strip of metal soldered to the netting, but may be formed by turning the

edge, or otherwise. The beads or ribs e , being 30 within the tubes c and wider than the slots, prevent the netting from being drawn out by pressure or blows upon it. They may be placed on the ends of the netting as well as the sides, if desired. I do not, however, limit myself to 35 the use of these beads or ribs, as they may be dispensed with.

The netting dash-board constructed as de-
scribed is light, strong, and ornamental.

The mesh may be of any size and the net- 40
ting of any metal.

I am aware that carriage-body frames have been made of tubing and light wrought-iron in which wire-netting is fitted, and therefore do not claim such; but 45

What I do claim, and desire to secure by Let-
ters Patent, is—

As an improved article of manufacture, a dash-board consisting of the outer frame, A, the inner frame, B, composed of slotted tub- 50
ing c , and the wire-netting d , fitted in the slot-
ted tubing of the said inner frame, substan-
tially as herein shown and described.

E. RATTEY.
